CLAIM

The ornamental design for a connector, as shown and described.

DESCRIPTION

The U.S. design patent application Ser. No. 29/614,043 filed on Aug. 15, 2017, entitled “Connector,” filed herewith, and is hereby incorporated by reference in its entirety.

All of the material from the U.S. design patent that is essential to the claimed design is included herein. Any material in the U.S. design patent that is not present herein forms no part of the claimed design.

FIG. 1 is a top and side perspective view of a connector embodying our new design;

FIG. 2 is a bottom and side perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a back view thereof.

Broken lines are used to illustrate portions of the connector or environmental subject matter that form no part of the claimed design. The dot-dash-dot and/or the diagonal shaped group of lines form the bounds of the claimed design and are not part of the claimed design.

The dot pattern areas represent areas of contrasting appearance. As shown in FIG. 1, the dot pattern areas of the front portion of the connector and the rounded rectangle in the middle of the connector represent areas of contrasting appearance. Similarly, FIGS. 2-7 show dot pattern areas that represent areas of contrasting appearance.
